UNITED STATES PATENT OFFICE.

GEORGE P. BRAND, OF NEW YORK, N. Y.

UNIT-ACTION FOR PNEUMATIC MUSICAL INSTRUMENTS.

1,308,159.

Specification of Letters Patent.

Patented July 1, 1919.

Application filed October 3, 1916. Serial No. 123,477.

To all whom it may concern:

Be it known that I, GEORGE P. BRAND, a citizen of the United States, and a resident of New York, in the county of the Bronx 5 and State of New York, have invented certain new and useful Improvements in Unit Action for Pneumatic Musical Instruments, of which the following is a specification.

The invention relates to musical instruments and is specifically adapted to the action chest in which the valves for actuating the player pneumatics are arranged and controlled.

The object of the invention is to provide 15 a condensed unified form of action chest well adapted to be placed directly in the instrument back of the "fall" board and in conjunction with the spool-box, in a condensed form, within the limits of which the wippines 20 or other connecting apparatus of the piano action may be readily connected and actuated.

A further object is to provide a unit valve construction which may be applied to or removed from the action chest and of a form 25 and construction which may be readily manufactured as a unit and applied within the chest.

Of course, the invention herein described 30 and shown is not limited to its particular application as illustrated by the drawings, but contemplates a unified valve-box and valve which may be applied to or removed from an instrument without disturbing the various 35 other valves and appurtenant parts which are utilized on each of the keys of the instrument.

Heretofore it has been a practice to build 40 up an action or valve chest with set and predetermined ducts, valves and other appurtenances which would actuate and control from the tracker-board the various key pneumatics.

The present invention has to do with an 45 "action chest" in which the valve units are separable—one for each player pneumatic—and each removable and adjustable. All of these valve actions are made an appurtenance of an individual player pneumatic or bellows, and all conditions of wind pressure 50 or suction together with the exhausts and the muffling of the exhausts are taken care of through the connections made between the valve actions and the player pneumatics all 55 and both of which are mounted upon a sin-

gle board or side of the suction or action chamber.

With the device herein described a most condensed form of apparatus is possible and a most simple type of device is made most 60 efficient.

The condensation is largely due to the form of unit valve apparatus which is conveniently mounted upon one wall of the exhaust or "action chamber".

The simplicity of the device exists through the individual unit form of valve construction combined and made adjustable upon the wall of the action chest and connected directly through said wall with the player 70 pneumatics.

As illustrated herein, three tiers of valves and pneumatics are shown but the number and disposition of the valve units and pneumatics may be varied.

The pneumatics may be of any type. The up-thrust principle is illustrated in the present case as being a convenient and at present a possible form of practice.

Referring to the drawings:

Figure 1 is an elevation with parts broken away showing the interior of the action chest and its valves.

Fig. 2 is an enlarged vertical section through the action chest showing the possible connections of the player pneumatics with the wippines of the piano action.

Fig. 3 is a horizontal section through the device.

Fig. 4 is a detail vertical section on enlarged scale of one of the valve units.

Fig. 5 is a plan view partially in section of one of the valve units.

It has been a practice to provide valve actions in conjunction with an exhaust chest 95 in which said actions have been connected to the exhaust chest or bellows either individually or in multiple and, of course, with a connection from the tracker-board for venting the valves so that the valves would 100 control the striker pneumatics.

It is one of the principal objects of the present invention to arrange all of the elements, from the striker pneumatics to the main suction, in a condensed form and a 105 unitary form so that the striker pneumatics may be readily mounted in a distinct and staple manner and will have a direct connection with the valve actions which control the same.

The drawings do not illustrate all of the parts of a pneumatically operated instrument but pertain to the valve actions and the striker pneumatic action or bellows.

- 5 Referring thereto, there is a suction or action chest 1, which may be formed in any convenient manner to comply with the exigencies of any desired construction of instrument. It has a main pressure or suction outlet 2, which is preferably formed in the end support 3. The suction or pressure is of course provided for in any desirable manner by bellows or other apparatus not specifically illustrated.
- 10 The suction or action chamber 1, is mounted upon suitable "blocks" not herein illustrated and comprise a supporting wall or board 4, which upon one side has supporting ledges 5, to which are secured the
- 15 striker pneumatics 6. These ledges 5, may be fastened to the supporting wall 4, in any desired manner, as by screws 7, and are of a form which give the necessary and desired position to the striker pneumatics 6.
- 20 Being separable from the wall 4, the ledges 5 may be readily bored to give an inner passage 8, from the striker pneumatics together with a second boring 9, at right angles or substantially at right angles there-
- 25 to. The bores 9 and 8, may be made readily and with accuracy and when the parts 5 are screwed into position they may be brought into exact registration with the openings 10, which are formed through the wall 4.
- 30 Two openings 10, are shown for each opening 9, in order to give a muffling effect to the ingress and egress of air from the valve mechanisms to the striker pneumatics 6.
- 35 The chest 1, is of course closed at its ends and has a removable front-board 11, upon the removal of which all of the valve mechanisms are made available.
- 40 The top of the chest is closed by a head-piece 12, which contains ducts 13, and is made in a composite structure with a removable duct piece 14, (secured in position by glue) having connections 15, by which the ducts 13, may be conveniently connected
- 45 to the tracker-board of an instrument.
- 50 Secured to the wall 4, is a block 16, to which are applied, in removable form, a series of levers 17, there being one lever for each striker pneumatic 6. There is a pivotal connection through the rod 18, with the movable board for each of the striker pneumatics, and there is an adjustable member 20, the lever 17, and the wippen 21, of the piano action where the device is used for a
- 55 piano.

Within the chest 1, are formed grooves 22, and supporting ledges 22^a; and upon these ledges rest the valve units 23.

These valve units are of course connected

65 through flexible or other connections 24, and are of a unitary construction which are removable and may be removed and replaced at will, as to any particular striker pneumatic with which they are utilized.

70 The valve units are properly insulated in their connection with the wall 4, so that there is no possibility of leakage of air and comprise essentially a unitary form of structure.

75 Each valve unit has a main casing 25, with a valve chamber 26, and a valve 27. The valve 27, is guided in its movement by a pin 28, and normally rests upon a valve seat 29. The unit has atmospheric openings 30, which connect directly with the ducts or openings 10, of the wall 4, and the valve is actuated or released by a diaphragm 31, whenever the tracker-duct 32, connecting with the tracker-ducts 13, is 80 opened to atmospheric pressure. There is, of course, a bleed hole 33, which equalizes the pressure above and below the diaphragm 31, when the chamber 1, is under ordinary pressure.

90 The operation between the valves and the striker pneumatics 6, is one which is generally well known.

95 Whenever one of the tracker-ducks is vented, atmospheric air entering below the diaphragm 31, submits the diaphragm to the suction of the chest 1. Thereupon, the valve stem of the valve 27, rises and carries with it the valve 27, opening the exhaust port 29, and closing the atmospheric port 29^a. This action gives direct suction 100 through the valve seat and port 29, to the striker pneumatics 6. A collapse of the striker pneumatic affected raises its particular lever 17, and through the adjustable 105 member 20, throws up the wippen 21, thus actuating the particular key of the instrument. Immediately thereafter the valve 27, re-seats itself upon the closing of the tracker-duct and re-action through the bleed 110 33. It will be noted that the perforations 10, being in multiple do not weaken a structure of the material or block 25, of the valve housing.

115 It is to be noted that the individual and unitary form of valves permits ready assembling and disassembling for repairs or replacements and, as illustrated herein, each pair of adjoining valve actions is held in place against the wall 4, by cross straps 34, 120 which bind the units of the wall 4, through suitable screw connections or other devices, illustrated herein as a screw 35.

125 From the above it is apparent that any one of the unitary valve actions may be removed and replaced without great inconvenience, and makes it possible to provide units for immediate replacement without disturbing the construction or connections through the wall 4. In fact, should the 130

valve mechanism of any particular unit "break down", it may be immediately removed and replaced by another unit. Furthermore, the arrangement provides for a 5 condensed form of apparatus in which all of the valve actions are immediately subject to the pressures of the chest 1, and in which it is possible to give said chest the minimum of dimensions.

10 The main suction and sustaining bellows for the chest are not specifically illustrated and, of course, may be of any desired type and form to provide the necessary tension within the chest 1.

15 Attention is called to the simplicity of form which adds greatly to the economy of manufacture. The wall 4, may be grooved in strips of any particular, convenient length. The valve units 23, may be made 20 up to exact form and scale and are readily adjustable to the grooves of the wall 4.

Attention is called to the valve actions of unitary form which have a main block 25^a, atmospheric ports 30 and a valve chamber 26. 25 The bottom of the chamber 26 is sealed by a strip or block 25^b, and below said block is the pouch carrying member 25^c.

The main valve block and the pouch member are connected by an intermediate element 25^d. The main valve block rests directly against the face of the wall 4, and the grooves provided in said wall permit an extension of the pouch member 25^e. This arrangement permits "off centering" the 35 valve spindle 28, and the valve 27, with the appurtenant parts so that the center of the pouch element 25^e, due to its extension within the groove of the wall, gives a considerable condensation in the whole structure.

40 In other words, by off centering the valve and appurtenant parts with reference to the valve block 25^a, and by arranging the diaphragm of the pouch member 25^e, so that it will extend into the channel of the wall 45 4, the width or thickness of the valve chest may be considerably reduced.

With the features above defined, it is possible to provide an action chest in which all of the valve actions are immediately accessible. It is furthermore possible to condense the thickness of the structure. Furthermore, the player pneumatics are directly connected to the exterior of the chest with certain and exact registrations of the connecting orifices between said pneumatics and the valve actions. The valve actions, as 55 units, have relief ports extending through the supporting wall of the chest, and the diaphragms are all subject to the same tension within the chest so that there is an equalization of pressure for operation of each of the diaphragms.

There is one very desirable feature of the unit valve construction which resides in the 60 entire exposure of the diaphragm member

and its close juxta-position to the valve stem, giving free egress of air below the valve port. This prevents wire-drawing of the air and gives an area of exhaust greatly exceeding the demands of the valve port itself. Therefore, the striker pneumatic will operate with greater speed and there is little or no liability of the relation of the valve and diaphragm changing to an extent which will throw the action out of adjustment. 70 75

In other words, the close relation of the diaphragm and valve spindle is such that there is no liability of shrinkage or swelling which will cause an abnormal condition. 80 The release conditions for the air from the striker pneumatics through the valve and over the diaphragm are of maximum proportion, and the distances between the diaphragm and its connection with the valve 85 are reduced to a minimum. It will be observed that practically three sides of the unit above the diaphragm are open for the passage of air.

Obviously the exact detail and construction of the various elements may be varied to suit the exigencies of any particular and desirable manufacture. The main thought is to provide unitary elements which will register and may be adjusted into position and removed from the chest at will. The connections with the striker pneumatics and the flexible or adjustable connections with the tracker-ducks permit of certain and definite connections between the unit valve 90 95 structures and their elements. 100

What I claim as my invention and desire to secure by Letters Patent is:—

1. A unit action comprising a complete action chest, individual valve actions within said chest, player pneumatics exteriorly arranged upon one wall of said chest, a removable duct piece having tracker duct connections for the valve actions and ducts connecting said valve actions with the player pneumatics, said duct piece being continuous of the member to which it is affixed. 105 110

2. In a device of the character described an action chest having grooves formed therein, removable valve actions adjustable in said grooves and means for holding said valve actions in adjusted position in said grooves. 115

3. In a device of the character described an action chest, striker pneumatics mounted upon one wall of said chest, ducts connecting said pneumatics with the interior of the chest, valve units controlling said ducts and means for adjustably securing said valve units within the chest in operable position 120 with reference to the connecting ducts of the striker pneumatics. 125

4. In a device of the character described an action chest, one of its walls being grooved and perforated, said groove receiv- 130

ing a portion of the diaphragm, striker pneumatics on the exterior of the wall, valve actions mounted upon the interior of the wall and means for removably securing said 5 valve actions to the wall in operable relation to the striker pneumatics and their ducts.

5. In a device of the character described an action chest having a wall perforated to 10 form connecting ducts between a valve mechanism and a striker pneumatic, separable carriers for the striker pneumatics, ducts formed therethrough and registering with the ducts of the wall, valve actions adjustable and removable within the chest and 15 means for removably securing said valve actions to the interior wall of the action chest.

6. In a device of the character described an action chest, unitary valve structures 20 adjustably mounted within said action chest and upon one wall thereof and arranged in pairs, a binding means extending over and holding each pair of valve actions, means for adjustably securing each pair of valve actions and striker pneumatics, and ducts connecting said pneumatics with the valve actions.

7. In a device of the character described an action chest, a series of individual valve 30 units adjustably mounted within said chest and upon the inner wall thereof, striker pneumatic supports mounted upon the outer side of the wall, ducts through said wall and said supports, a series of striker pneumatics 35 permanently mounted upon said supports, a rail removably secured to said wall, actuating levers and connections between said rail and the striker pneumatics—one for each pneumatic, tracker-duct connections 40 and a removable and renewable duct member between said tracker-duct connections and the individual valve actions.

8. In a device of the character described an action chest, end supports and a grooved 45 wall therefor to receive the adjacent portion of a diaphragm, individual valve actions removably secured to said wall within the chest, player pneumatics corresponding to the valve actions removably secured to the 50 exterior wall of the chest, and ducts connecting the player pneumatics and the valve actions.

9. In a device of the character described an action chest, end supports and a grooved 55 wall therefor to receive the adjacent portion of a diaphragm, individual valve actions removably secured to said wall within the chest, player pneumatics corresponding to the valve actions removably secured to the 60 exterior wall of the chest, ducts connecting the player pneumatics and the valve actions, and a removable wall giving access to all of said valve actions.

10. In a device of the character described

an action chest, one of its walls being 65 grooved and adapted to receive adjacent portions of the diaphragm of the valve actions, valve actions of unit form within said chest and applicable to said wall and means for binding said valve actions in pairs to 70 said wall.

11. In a device of the character described an action chest having one of its walls grooved and adapted to receive the valve actions, valve actions of unit form applicable to said wall, a binding strap overlying each two adjacent valve actions and means for binding said strap against the actions and said actions against the grooved wall. 75

12. In a device of the character described 80 an action chest, one of its walls being grooved to receive the adjacent portions of the diaphragms longitudinally and perforated, unitary valve actions perforated to register with the perforations through the 85 wall, player pneumatics having ducts registering with the wall openings and means for clamping each pair of adjacent valve actions in position.

13. In a device of the character described, 90 an action chest having a removable wall and a perforated wall, one of which walls is grooved and adapted to receive the adjacent portion of the diaphragm of an action unit, a valve unit applicable to the interior 95 wall of the action chest, a detachable member having connecting ducts, and striker pneumatics arranged upon the exterior of said grooved wall.

14. In a device of the character described 100 an action chest having a removable wall and a perforated wall, a series of striker pneumatics operatively mounted upon the exterior of said perforated wall, valve actions mounted upon the interior of said wall and 105 arranged in pairs, means for holding each pair of valve actions removably and adjustably against said wall, ducts through said wall connecting the striker pneumatics and valve actions, and ducts adjustably connected with said valve actions through which 110 the latter are actuated.

15. In a device of the character described 115 an action chest, one of the walls of said chest being grooved, striker pneumatics exteriorly mounted upon one wall thereof, said groove adapted to receive the adjacent portion of the diaphragm, ducts connecting said striker pneumatics with the interior of the chest through the wall, unit valve actions 120 adjustable with reference to said ducts and removable with respect to the wall, all of said valve actions subject to the tension of the action chest, individual connections with each of said valve actions controlling the 125 action of the suction with reference to each of the valve units, and means for removably securing the valve units to said wall.

16. In a device of the character described an action chest, one of the walls of said chest being grooved, a plurality of valve members within said chest and each having an exhaust through one wall of the chest and having an open diaphragm connection with the interior of the chest, a valve arranged in the valve chamber of each valve member and a duct communicating with each valve chamber and with a striker pneumatic, said groove adapted to receive the adjacent portion of the diaphragm. 65
- 5 17. In a device of the character described, an action chest subject to air tension, one of the walls of said chest being grooved, a plurality of individual unit valve structures arranged therein and removable therefrom, each individual unit comprising a valve block with relief ports, a valve, a diaphragm controlling the operation of said valve and suspended with reference to the valve block and open to the suction of the chest, said diaphragm having an area greater than the block but with its center coincident with the 70 20 valve of said block, said groove adapted to receive the adjacent portion of the diaphragm. 25
- 15 18. In a device of the character described an action chest, a plurality of separable valve units removably mounted therein upon one wall of said chamber and each comprising a valve chamber and valve arranged concentrically with reference to an actuating diaphragm, a diaphragm member suspended from the valve block and a diaphragm for actuating the valve, a wall of the chest being grooved to receive the adjacent portions of the diaphragms, atmospheric ports for the valve block, communicating channels 30 35 from said ports to the exterior of the valve chest and connections for controlling the action of the diaphragm. 40
- 45 19. In a device of the character described, an action chest adapted to receive a series of valve mechanisms and having one of its walls grooved to receive the adjacent portions of the diaphragms of said valve mechanisms. 50
- 55 20. In a device of the character described, an action chest adapted to receive a series of valve mechanisms and having one of its walls grooved to receive the adjacent portions of the diaphragms of said valve mechanisms and provided with atmospheric exhaust ports. 55
- 60 21. In a device of the character described a valve chest having one of its walls grooved and provided with atmospheric and exhaust ports, striker pneumatics registering with the ports upon one side, and valve mechanisms registering with the ports upon the opposite side with their adjacent portions received within said grooves. 65
- 65 22. In a device of the character described a valve chest having one of its walls grooved and provided with atmospheric and exhaust ports, striker pneumatics registering with the ports upon one side, valve mechanisms registering with the ports upon the opposite side, said valve mechanisms having a part 70 extending into said groove. 75
- 75 23. In a device of the character described a valve chest having one of its walls grooved and provided with atmospheric and exhaust ports, striker pneumatics registering with the ports upon one side, valve mechanisms registering with the ports upon the opposite side, said valve mechanisms having a part 80 extending into said groove, and means for binding said valve mechanisms to said board. 85
- 80 24. In a device of the character described an action chest having one of its walls grooved and perforated and providing atmospheric and exhaust ducts, the grooves being adapted to receive the adjacent portions of the diaphragms, striker pneumatics controlled by said ducts and mounted upon one side of said wall, valve actions controlling said ducts and mounted upon the opposite side of said wall. 90
- 90 25. In a device of the character described an action chest having one of its walls grooved and perforated and providing atmospheric and exhaust ducts, the grooves being adapted to receive the adjacent portions of the diaphragms, striker pneumatics controlled by said ducts and mounted upon one side of said wall, valve actions controlling said ducts and mounted upon the opposite side of said wall, and means for removably securing the striker pneumatics 95 and the valve actions to said board. 100
- 100 26. In a device of the character described an action chest having one of its walls grooved and perforated and providing atmospheric and exhaust ducts, the grooves being adapted to receive the adjacent portions of the diaphragms, striker pneumatics controlled by said ducts and mounted upon one side of said wall, valve actions controlling said ducts, and mounted upon the opposite side of said wall, means for removably securing the striker pneumatics and the valve actions to said wall, and means for removably securing the valve actions in adjustable position upon said wall. 105
- 110 27. In a device of the character described an action chest having one of its walls grooved and perforated and providing atmospheric and exhaust ducts, the grooves being adapted to receive the adjacent portions of the diaphragms, striker pneumatics controlled by said ducts and mounted upon one side of said wall, valve actions controlling said ducts and mounted upon the opposite side thereof, means for removably securing the striker pneumatics and the valve actions to said wall, means for removably securing 115
- 120
- 125

the valve actions in adjustable position upon said wall, and flexible connections for said valve actions.

28. In a device of the character described 5 an action chest having one of its walls grooved, striker pneumatics mounted exteriorly thereof, the grooves being adapted to receive the adjacent portions of the diaphragms, ducts extending through a wall of 10 the chest and controlling the striker pneumatics, and valve actions removably secured within the chest and controlling said ducts.

29. A valve action applicable to the wall 15 of an action chest having one of its walls grooved having port openings to register with ducts through the wall of said chest and provided with a diaphragm open as to its entirety to the suction action of the chest, the grooves being adapted to receive 20 the adjacent portions of the diaphragms.

30. An action chest having one of its walls grooved to receive the adjacent portions of the diaphragms of valve units, a plurality 25 of valve units, and operative connections from the chambers of the valve units.

31. An action chest, a plurality of valve units within said chest and operative connections from the chambers of the valve units, a removable duct piece with ducts 30 and a head piece for said valve chest having a plurality of ducts one for each of said valve units.

32. An action chest, a plurality of valve units within said chest, operative connections 35 from the chambers of the valve units, a head piece for said valve chest having a plurality of ducts one for each of said valve units, and coöperating with the ducts of the head piece and a removable duct piece co- 40 operative with said head piece.

33. In a pneumatic action for musical instruments, the combination of an action chest having one of its walls longitudinally grooved, a vacuum chamber casing, a series 45 of primary pneumatic elements and valve casings arranged wholly within the vacuum chamber casing, the grooves being adapted to receive the adjacent portions of the diaphragms, valves within the valve casings 50 and inclosed thereby and power pneumatics one for each valve casing arranged without the vacuum chamber casing and operatively associated with the valve casings.

34. In a pneumatic action for musical instruments, the combination of an action chest having one of its walls longitudinally grooved, a vacuum chamber casing, a valve casing positioned within the vacuum chamber casing, the grooves being adapted to receive 55 the adjacent portions of the diaphragms, a primary pneumatic operatively associated with the valve casing, a motor pneumatic arranged without the vacuum chamber casing, means for establishing di-

rect communication between the valve casing and the motor pneumatic through one wall of the vacuum chamber casing, and means for detachably supporting the motor pneumatic and valve casing on said wall of the vacuum chamber casing. 65

35. In a pneumatic action for musical instruments, the combination of an action chest having one of its walls longitudinally grooved, a vacuum chamber casing, a valve casing positioned within the vacuum chamber casing, the grooves being adapted to receive the adjacent portions of the diaphragms, a primary pneumatic operatively associated with the valve casing, a motor pneumatic arranged without the vacuum chamber casing, one wall of the vacuum chamber casing having an opening therethrough, and the valve casing and motor pneumatic having registering ports adapted to establish communication with one another 80 through said opening of the vacuum chamber casing. 85

36. In a pneumatic action for musical instruments, the combination of an action chest having one of its walls longitudinally 90 grooved, a vacuum chamber casing, a valve casing positioned within the vacuum chamber casing, the grooves being adapted to receive the adjacent portions of the diaphragms, a primary pneumatic operatively 95 associated with the valve casing, a motor pneumatic arranged without the vacuum chamber casing, means for establishing communication between the valve casing and the motor pneumatic, means for detachably sup- 100 porting the motor pneumatic and valve casing on the vacuum chamber casing, and a removable closure for the vacuum chamber casing permitting access to the primary pneumatic and valve casing. 105

37. In a pneumatic action for musical instruments, the combination of an action chest having one of its walls longitudinally grooved, a supporting wall, a valve casing, a motor pneumatic, the grooves being adapted 110 to receive the adjacent portions of the diaphragms, said supporting wall having an opening therethrough, and said motor pneumatic and valve casing having an opening in one wall thereof, and means for supporting 115 the valve casing and motor pneumatic upon opposite sides of said supporting wall whereby the openings thereof directly register with the opening in the supporting wall.

38. In a pneumatic action for musical instruments, the combination of an action chest having one of its walls longitudinally grooved, a primary pneumatic casing, valves, a valve casing inclosing said valves and mounted upon the primary pneumatic casing, 120 the grooves being adapted to receive the adjacent portions of the diaphragms, and an inclosing casing for the primary pneumatic 125

casing and valve casing, said inclosing casing forming a vacuum chamber.

39. In a pneumatic action for musical instruments, the combination of an action chest having one of its walls longitudinally grooved, a primary pneumatic element, a valve casing mounted thereon, an inclosing vacuum chamber casing for the primary pneumatic element and common valve casing, the grooves being adapted to receive the adjacent portions of the diaphragms, and means engaging one wall of the inclosing casing for detachably supporting both the primary pneumatic element and valve casing in place.

40. In a pneumatic action for musical instruments, the combination of an action chest having one of its walls longitudinally grooved, a primary pneumatic casing, a valve casing mounted thereon, an inclosing casing independent of the main casing of the instrument for the primary pneumatic and valve casings, the grooves being adapted to receive the adjacent portions of the diaphragms, and means engaging one wall of the inclosing casing for detachably supporting both the primary pneumatic and valve casings in place, and a movable closure for the inclosing casing permitting access to said detachable parts.

41. In a pneumatic action for musical instruments, the combination of an action chest having one of its walls longitudinally grooved, a primary pneumatic, a valve casing operatively connected therewith, the grooves being adapted to receive the adjacent portions of the diaphragms, a vacuum chamber casing, the said primary pneumatic and valve casing being positioned within and inclosed by the vacuum chamber casing.

42. In a pneumatic action for musical instruments, the combination of an action chest having one of its walls longitudinally grooved, a primary pneumatic element, a valve casing secured thereto, a vacuum chamber casing, the said primary pneumatic element and valve casing being positioned within and inclosed by the vacuum chamber casing, said vacuum chamber casing having an opening leading to the outside and communicating with the valve casing.

43. In a pneumatic action for musical instruments, the combination of an action chest having one of its walls longitudinally grooved, a primary pneumatic casing, a valve casing connected directly thereto, the grooves being adapted to receive the adjacent portions of the diaphragms, a vacuum chamber casing, the said primary pneumatic

and valve casings being positioned within 60 and inclosed by the vacuum chamber casing, and a conduit within the casing communicating with the primary pneumatic casing and leading to the outside of the casing for connection with a tracker bar.

65

44. In a pneumatic action for musical instruments, the combination of an action chest having one of its walls longitudinally grooved, a primary pneumatic, a valve casing connected thereto, the grooves being 70 adapted to receive the adjacent portions of the diaphragms, a vacuum chamber casing, the said primary pneumatic and valve casing being positioned within and inclosed by the vacuum chamber casing, and a conduit 75 within the casing communicating with the primary pneumatic and leading to the outside of the casing for connecting with a tracker bar, said conduit being formed in sections, whereby to permit removal of the 80 valve casing and primary pneumatics.

45. In a pneumatic action for musical instruments, the combination of an action chest having one of its walls longitudinally grooved, a primary pneumatic casing, a 85 valve casing mounted thereon, the grooves being adapted to receive the adjacent portions of the diaphragms, a vacuum chamber casing, the said primary pneumatic and valve casings being positioned within and inclosed by the vacuum chamber casing, and a conduit within the casing communicating with the primary pneumatic casing and leading to the outside of the casing for connection with a tracker bar, said conduit having 90 a vent opening within the vacuum chamber.

46. In a pneumatic action for musical instruments, an action chest, a head-piece with a plurality of ducts in vertical series, and a 100 removable duct-piece having corresponding ducts.

47. In a pneumatic action for musical instruments, an action chest having a removable wall, a head-piece with a plurality of 105 ducts in vertical series, and a removable duct-piece having corresponding ducts.

48. In a pneumatic action for musical instruments, an action chest having a removable wall, valve mechanisms and their casings within said chest, and operative connections from the casings of the valve mechanisms, and a removable duct-piece having a plurality of ducts.
